UNITED STATES PATENT OFFICE.

CHARLES L. CHRISTMANN, OF ENGLEWOOD, NEW JERSEY.

DESIGN FOR A BED-QUILT.

No. 38,390.

Specification for Design.

Patented Dec. 25, 1906.

Application filed October 18, 1906. Serial No. 339,861. Term of patent 3½ years.

To all whom it may concern:

Be it known that I, CHARLES L. CHRISTMANN, a citizen of the United States, residing at Englewood, in the county of Bergen and State of New Jersey, have invented a new, original, and ornamental Design for Bed-Quilts, of which the following is a specification, reference being had to the accompanying drawing, forming part thereof.

The figure is a plan view of a bed-quilt, showing my new design.

I claim—

The ornamental design for a bed-quilt, as shown.

CHARLES L. CHRISTMANN.
